MECHANICAL LIGHTER

Walter H. Roll, Linden, N. J.

Application June 4, 1937, Serial No. 146,463

9 Claims. (Cl. 67—7.1)

This invention relates to mechanical lighters of the types usually referred to as cigar or cigarette lighters, and the primary object of the invention is to provide, in such a lighter, unique structure that will afford a closed passageway for the sparks, created by flint and file, as they move toward the wick.

Another important aim of the invention is the provision of a mechanical lighter, wherein the relatively movable flint and file, which are usually employed to produce sparks, are housed within a closed passageway extending from the zone of spark production to a point immediately adjacent to the wick, so that as the sparks pass from flint and file to the wick, the same cannot be acted upon by air currents which invariably lower the efficiency of any mechanical lighter, and under some conditions render the same definitely inoperative.

A yet further aim of this invention is to provide a mechanical lighter of the conventional type, with flint and file spark producing elements that are actuated simultaneously with the movement of the hinged cover, to the end that but one action on the part of the operator is necessary to both open the cover of the lighter and relatively move the flint and file therein.

Still further objects of the invention include the unusually simple, effective and durable mechanism, which may embody the broader and specific concepts of the invention; and such minor objects will appear during the course of the following specification, referring to the accompanying drawings, wherein:

Figure 1 is a vertical, central, sectional view through a mechanical lighter made in accordance with the present invention.

Fig. 2 is a front edge elevation of the same.

Fig. 3 is a fragmentary, vertical, central, sectional view through the upper portion of the mechanical lighter illustrated in Fig. 1, but with the cover in the open position.

Fig. 4 is a front edge elevation of the upper portion of the open lighter, as it is shown in Fig. 3.

Fig. 5 is a fragmentary, detailed, sectional view, taken along line V—V of Fig. 1.

Fig. 6 is an irregular horizontal, sectional view through the mechanical lighter, taken on line VI—VI of Fig. 1.

Fig. 7 is a vertical, central, sectional view through a mechanical lighter similar to that illustrated in Figs. 1 to 6 inclusive, but constructed to embody a modified form of the invention.

Fig. 8 is a front edge elevation of the lighter shown in Fig. 7.

Fig. 9 is a fragmentary, central, sectional view through the upper portion of the lighter illustrated in Fig. 7, but with the cover in the open position.

Fig. 10 is a front edge elevation of the upper portion of the lighter as it is illustrated in Fig. 9, and,

Fig. 11 is a horizontal, sectional view, taken along line XI—XI of Fig. 9.

The broad concepts of this invention are embodied in both the form of mechanical lighter shown in Figs. 1 to 6 inclusive and that form shown in Figs. 7 to 11 inclusive.

In both forms, the mechanical lighter comprises a two-part case 14. The upper part houses and carries the mechanical parts and wick and has a vent hole 16 formed therein. A base member 18, forming a portion of the lower part, is provided with a filler plug 20, through which may be introduced the combustible liquid that is usually employed to impregnate a wick 22. A filling of cotton or like fibrous material in the lower part of housing 14 aids in holding the combustible liquid and in keeping the wick 22 in proper operative condition over a long period of time. A portion 26 of wick 22 is projected outwardly through the bottom wall of the upper portion of case 14. The one end of wick 22, which is projected, is that end against which impinges a train of sparks that are formed when the cover of the lighter is opened upon the release of spring catch 28. Spring catch 28 is of conventional form, has one end anchored as at 30 to one wall of the upper part of case 14, while the other end engages pin 32 mounted on the hereinafter numbered covers. The finger button 34 extends through the wall of case 14 so that upon pressing button 34 inwardly spring catch 28 will release the cover.

With specific reference now to the form of the invention shown in Figs. 1 to 6, it will be apparent from the drawings that cover 36 is hingedly mounted upon the upper portion of case 14 through the medium of hinge pintle 38. A spring 40, wound about pintle 38, serves to yieldably urge cover 36 toward the open position shown in Fig. 3, and a combined stop and closing knob 42 abuts the edge 44 of case 14 to arrest the opening movement of cover 36.

A suitable spacer 46 may be provided to maintain the sides of case 14 in place and to serve as means for holding roller frame 47 against displacement. A series of flanged rollers 48, extend-

ing across from side to side of frame 47, carry an endless, flexible steel belt 50. This belt 50 has its ends attached to cover 36 to make it an endless element, and when opening cover 36 from the position shown in Fig. 1 to that shown in Fig. 3, the belt 50 is carried around rollers 48. The form of roller frame 47 is such as to permit free movement of cover 36 to the open position.

A file 52, secured to belt 50 for movement therewith, is reciprocated as cover 36 is opened and closed. The serrations 54 formed on one side of file 52 directly engage flint 56, and when file and flint are brought together in the fashion indicated, sparks are formed. Flint 56 is yieldably held against serrations 54 of file 52 by spring 58. An adjusting screw cap 60 may be manipulated to vary the tension of spring 58. The zone of contact between file 52 and flint 56 is within a specially disposed tube 62. This tube 62 not only houses the contacting portions of file and flint 52 and 56 respectively, but extends to a point immediately adjacent to the projected end 26 of wick 22. This tube 62 also presents an enclosed passageway for sparks, and the cross sectional area of the tube progressively decreases as wick portion 26 is approached from the flint.

Sparks formed within tube 62 by the movement of file 52 across the end of flint 56 will be directed out the end of tube 62 because of the quick action of the file. These sparks will be concentrated into a stream which impinges directly upon portion 26 of wick 22 and therefore create a more positive lighting action.

The form of invention illustrated in Figs. 7 to 11 inclusive embodies the same broad concepts with respect to the provision of a tube, but the specific structural form is somewhat varied from that just described. In this instance, cover 64 is mounted for hinging movement upon hinge pin 66, carried by the upper portion of case 14. A spring 68 yieldably urges cover 64 to the open position shown in Fig. 9, and a stop 10 limits the opening action. Hinge pin 66 passes through a specially formed tube 72, wherein is mounted a disc-shaped file 74.

Serrations 76, formed upon the annular face of file 74, engage one end of flint 78 when the file is rotated. Pin 66 is squared so that file 74 and cover 64 move together. Flint 78 is yieldably held against file 74 by spring 80, and an adjustable cap 82 may be manipulated to vary the tension of spring 80. Tube 72 houses the spark forming portions of file 74 and flint 78, and the tube 72 extends to a point immediately adjacent to the projected portion 26 of wick 22. Sparks created by the movement of file 74 over flint 78 are directed outwardly toward wick portion 26 and tube 72 will afford a completely closed way so that drafts or outside forces will not alter the sparks as they move from point of origin to a place of impingement upon portion 26.

It is obvious from the foregoing that a mechanical lighter embodying the concepts of this invention might assume physical characteristics even different from those illustrated and described, and it is therefore desired to be limited only by the scope of the appended claims.

Having thus described the invention, what is claimed as new and desired to be secured by Letters Patent is:

1. A mechanical lighter of the character described comprising a case for receiving combustible fluid; a wick having a portion thereof in the case; a flint; a relatively movable file positioned for engagement with the flint as the file

is moved to produce sparks; and a tube extending from the flint and file to a point adjacent to one end of the wick for conveying the sparks from the flint and the file and for directing the sparks onto said one end of the wick.

2. A mechanical lighter of the character described comprising a case for receiving combustible fluid; a wick having a portion thereof in the case; a flint; a relatively movable file positioned for engagement with the flint as the file is moved to produce sparks; and a tube extending from the flint and file to a point adjacent to one end of the wick for conveying the sparks from the flint and the file and for directing the sparks onto said one end of the wick, said flint and said file being arranged within a portion of the tube.

3. A mechanical lighter of the character described comprising a case for receiving combustible fluid; a wick having a portion thereof in the case; a flint; a relatively movable file positioned for engagement with the flint as the file is moved to produce sparks; and a tube extending from the flint and file to a point adjacent to one end of the wick for conveying the sparks from the flint and the file and for directing the sparks onto said one end of the wick, said tube progressively decreasing in cross sectional area as the wick is approached from the flint and file.

4. A mechanical lighter of the character described comprising a case; a wick having a portion thereof projected from the case; a flint; a file movable across the flint to produce sparks; a tube extending from the flint to a point adjacent to the said projected portion of the wick to provide a closed passage for the sparks; a cover for the projected portion of the wick, hingedly mounted on the case; and mechanism interconnecting the file and said cover for moving the file across the flint as the cover is manipulated to and from the closed position.

5. A mechanical lighter of the character described comprising a case; a wick having a portion thereof projected from the case; a flint; a file movable across the flint to produce sparks; a tube extending from the flint to a point adjacent to the said projected portion of the wick to provide a closed passage for the sparks; a cover for the projected portion of the wick, hingedly mounted on the case; a spring yieldably urging the cover to the open position; a latch to hold the cover closed; and mechanism interconnecting the file and said cover for moving the file across the flint as the said spring forces the cover to the open position.

6. A mechanical lighter of the character described comprising a case; a wick having a portion thereof projected from the case; a flint; a file movable across the flint to produce sparks; a tube extending from the flint to a point adjacent to the said projected portion of the wick to provide a closed passage for the sparks; a cover for the projected portion of the wick, hingedly mounted on the case; a spring yieldably urging the cover to the open position; a latch to hold the cover closed; and mechanism interconnecting the file and said cover for moving the file across the flint as the said spring forces the cover to the open position, the end of said tube adjacent to said wick being protected by said cover when the latter is in the closed position.

7. In a mechanical lighter of the kind described having a wick, the combination of a tube terminating adjacent to one end of the wick; a

file movably mounted within the tube a distance from the wick; and a flint yieldably held against the file whereby sparks produced by the movement of said file over the said flint are provided with a closed path of travel from point of origin to a zone immediately adjacent to said wick.

8. A mechanical lighter of the character described comprising a case; a wick having a portion thereof projected from the case; a flint; a file movable across the flint to produce sparks; a tube extending from the flint to a point adjacent to the said projected portion of the wick to provide a closed passageway for the sparks between point of origin and the wick; a cover hingedly mounted on the case; an endless belt carrying the said file; and a series of rollers carrying the belt, said belt being attached to said

cover for movement over the rollers to carry the file when the cover is moved.

9. A mechanical lighter of the character described comprising a case; a wick having a portion thereof projected from the case; a flint; a file movable across the flint to produce sparks; a tube extending from the flint to a point adjacent to the said projected portion of the wick to provide a closed passageway for the sparks between point of origin and the wick; a cover hingedly mounted on the case; and a hinge pin rotatable about its axis with the cover when the latter is moved, said file being disc-shaped and mounted upon said hinge pin for rotation therewith, the annular edge of said file being serrated along the surface thereof which moves across the flint.
